Frank M. Brooks, Inventor
By his Attorney Phillips Abbott

UNITED STATES PATENT OFFICE.

FRANK M. BROOKS, OF BROOKLYN, NEW YORK.

INCANDESCENT GAS-LAMP.

SPECIFICATION forming part of Letters Patent No. 705,818, dated July 29, 1902.

Application filed October 4, 1901. Serial No. 77,512. (No model.)

To all whom it may concern:

Be it known that I, FRANK M. BROOKS, a citizen of the United States, and a resident of Brooklyn, in the county of Kings and State of New York, (having my post-office address at No. 35 Warren street, New York, N. Y.,) have invented certain new and useful Improvements in Incandescent Gas-Lamps, of which the following is a specification.

- 10 The mantles used on this class of gas-lamps are, as is well known, exceedingly fragile. The slightest blow or jar is liable to fracture them. Heretofore a frequent cause for the breaking of the mantles has been applying and removing the globe of the lamp for the purpose of cleaning or otherwise and also the movement of the chains or equivalent devices which operate the stop-cock to turn the gas on and off.
- 15 My improvements therefore consist in locating the devices which support the globe below the burners and so constructing them that the connection between the globe-holder and the gallery or support whereby it is held to the lamp may be easily, quickly, and smoothly made without any nicety of adjustment and without jar, such as has been necessary when threaded or slotted parts or confining means are required.
- 20 Another feature of my invention is the location of the gas-cock and the regulating devices, including the chains, cross-bar, pilot-tube connection, &c., not only below the burners, but also below the globe-support, so they may be in plain sight, easy of access, and free from proximity to the mantles, for when these parts are above the burners the movement of the cross-bar which actuates the cock and the inevitable movement 25 of the chains are apt to fracture the mantles. Furthermore, the chains, the stop-cock, the barrel for the stop-cock, and the other parts when located above the burners or adjacent to them are apt to get very much heated, whereby they contract and expand in such 30 manner as to jam or fail to move smoothly, whereupon the operator is very apt to jerk upon the chains with more or less violence, and this also is exceedingly apt to fracture 35 the mantles.

Referring now to the drawings, Figure 1 illustrates a vertical sectional view of the

apparatus, the burner, mantles, &c., being mostly shown in elevation. Fig. 2 is a view from beneath of the burner, globe-holder, &c. 55 Fig. 3 is a detail of the stop-cock and burner-casting. Fig. 4 is a detail of the cock separated from its barrel and all adjoining parts.

A represents the pipe by which the burner as a whole is suspended and through which 60 the gas is supplied. It is threaded or otherwise connected to the upper end B of the gas-chamber C, from which extend laterally the burner-supply tubes D, which connect with the burners E, (see Fig. 1,) upon which are 65 mounted the mantles F in the usual manner. Any other suitable support may be substituted for the pipe A, the gas being conveyed to the burner in such manner as preferred. The gas-chamber C is practically divided into 70 two chambers by a diaphragm G, threaded centrally, in which is screwed a pipe H, which is threaded at its lower end to the gas-cock I. This cock has a cup-shaped part at its upper end, which is threaded, as shown, and to 75 which the lower end of the gas-chamber C is connected by means of the threaded part L. The gallery or support M for the globe is clamped between the upper edge of the gas-cock, as at K, and a shoulder formed on the 80 gas-chamber C, as shown. The gallery has holes or perforations N in its lower part or bottom for the purposes of draft. The cock of the burner is provided with a lateral port O, which engages with a longitudinal port P, 85 from which in turn extend other ports Q Q, which engage with passages R in the barrel of the cock which communicate with the chamber.

S is the globe, and it has a flange T at its 90 lower end which rests in a cup-shaped globe-supporter U. One or more set-screws V may be employed to hold the globe firmly within the holder.

The gallery M has upon its sides three or 95 more ribs W, and the globe-holder U has a horizontal flange or partial bottom from which are cut recesses Y, leaving ledges Y' between them, the recesses having somewhat more area in all directions than the ledges W on 100 the gallery, as shown in Fig. 2, so that the globe-holder, carrying the globe with it, may be lifted from below straight upwardly and the ledges W on the gallery or support pass

through the recesses Y in the holder. Then by a circular movement of about one-third of a circle an engagement similar to a bayonet-slot lock will be effected between the ledges 5 W on the gallery and the ledges Y' on the globe-holder and the globe permanently held in proper position.

In order to prevent the possibility of the globe moving backwardly, so as to unlock 10 and fall, I provide stops a b (see Fig. 2) on the globe-holder, which engage with the ends of the ledges W on the gallery or support. The stop a is a small one having relatively slight 15 downward extension, so that it engages with the end of the appropriate ledge only when the parts are in place, there being sufficient looseness in the joint to permit this small projection passing above the ledge during the adjustment of the globe upon the gallery.

20 c is a tube for supplying the pilot-burner, which is furnished with gas in a manner now well understood through a passage-way f, cut in the periphery of the plug of the cock.

25 d is the cross-bar, which actuates the gas-cock P by means of the chains e e.

It will be observed that the means employed whereby the globe-holder is attached to the gallery or support are exceedingly simple and reliable and that the adjustment may be 30 made without danger of jarring, shaking, or striking the mantles. There is no tight fit at any part of the structure. The ledges on the gallery or support pass freely through the recesses in the globe-holder, and then by a 35 simple partial rotation of the latter the engagement is effectively and securely made, as stated. It will also be noted that the gas-cock and all coacting parts are below the burners. Therefore the actuating-chains and 40 the cross-bar and pilot-tube connection are removed from the mantles, so their movements do not tend to break them, and also that these parts are below the globe, and consequently are in the freely-circulating open 45 air, free from any confinement, thereby relieved of the great heat generated by the burners.

It will be obvious to those who are familiar with this art that modifications may be made 50 in the details of construction without departing from the essentials of the invention.

Having described my invention, I claim—

1. In an incandescent gas-lamp the combination of a globe-holder provided with a horizontal flange having recesses and ledges 55 between the recesses, a gallery connected with the burner having projections adapted to pass through the recesses in the flange of the holder to engage with the ledges on it and provided also with air-holes in its bottom 60 and a gas-cock and operating devices therefor located in the freely-circulating air below the burners and below the globe-support.

2. In an incandescent gas-lamp the combination of a globe-holder provided with an 65 inwardly-extending horizontal flange having a centrally-located opening large enough to permit the easy passage therethrough of the operating devices for the gas-cock, the inner edge of said flange having recesses and ledges 70 between the recesses, a gallery connected with the burner having a perforated bottom for the free passage of the air and having also projections adapted to pass through the recesses in the flange of the globe-holder and 75 to engage with the ledges thereof and a gas-cock and operating devices therefor located below the globe-support.

3. In an incandescent gas-lamp the combination of a globe-holder provided with an 80 inwardly-extending horizontal flange, said flange having a central opening large enough to permit the devices which operate the gas-cock to pass freely through it, recesses and ledges between the recesses on the inner edge 85 of said flange, a gallery connected with the burner and having projections adapted to pass through the recesses in the flange of the holder to engage with the ledges thereof, locking devices engaging with inside ledges 90 and projections which prevent accidental disengagement of the said parts and a gas-cock and operating devices therefor located below the burners.

Signed at New York, in the county of New 95 York and State of New York, this 2d day of October, 1901.

FRANK M. BROOKS.
